UNITED STATES PATENT OFFICE.

OTIS A. MYGATT, OF NEW YORK, N. Y.

DESIGN FOR A GLASS SHADE OR REFLECTOR.

46,347.

Specification for Design.

Patented Sept. 1, 1914.

Application filed June 5, 1908. Serial No. 436,992. Term of patent 14 years.

To all whom it may concern:

Be it known that I, OTIS A. MYGATT, a citizen of the United States, residing at New York, in the county of New York and State of New York, have invented a new, original, and ornamental Design for Glass Shades or Reflectors, of which the following is a specification, reference being had to the accompanying drawing, forming part thereof.

Figure 1 is a top plan view, and Fig. 2 is an elevation of a reflector embodying my invention.

My design is applied to glass shades and reflectors and consists of bands of radial

prisms extending substantially from the neck to the periphery thereof. Intermediate the bands of prisms the surfaces are plane.

I claim—

The ornamental design for glass shades or reflectors consisting of bands of radial prisms extending substantially from the neck portion to the periphery thereof and plane surfaces between the said bands, substantially as shown and described.

OTIS A. MYGATT.
